UNITED STATES PATENT OFFICE.

WILLIAM C. CHESNUT, OF RACINE, WISCONSIN, ASSIGNOR TO HARTMANN TRUNK COMPANY, OF RACINE, WISCONSIN, A CORPORATION OF WISCONSIN.

TRUNK CUSHION AND RETAINER.

Application filed September 17, 1923. Serial No. 663,262.

This invention relates to improvements in trunk cushion and retainer. Wardrobe trunks as now manufactured are formed in two sections adapted to stand 5 on end, and one of said sections is provided with garment hangers at its upper end for suspending wearing apparel therefrom. Medially of the height of the wardrobe section, garment retainers are provided, which are 10 adjustable toward and away from the rear portion of the trunk section to engage medial portions of the garments and firmly press them against the rear portion of said trunk section. As thus engaged, the vibration in- 15 cident to transportation very often abrades or otherwise injures the apparel.

It is one of the objects of the present invention to overcome the above mentioned objectionable feature and provide a trunk 20 cushion and retainer adapted to firmly hold the apparel without liability of injury thereto.

A further object of the invention is to provide a trunk cushion and retainer having 25 yielding means formed of a material which will firmly hold the apparel without injury thereto.

A further object of the invention is to provide a trunk cushion and retainer which 30 is of simple construction, is strong and durable, and is well adapted for the purpose described.

With the above and other objects in view, the invention consists of the improved trunk 35 cushion and retainer and its parts and combinations as set forth in the claims, and all equivalents thereof.

In the accompanying drawing, in which the same reference characters indicate the 40 same parts in all of the views:

Fig. 1 is a side view of a wardrobe trunk with the wardrobe section being shown in section to show the improved construction;

Fig. 2 is a side view of the retainer bar 45 on a larger scale;

Fig. 3 is an edge view thereof; and

Fig. 4 is a sectional detail view on a larger scale of the wardrobe section and the cushion and retainer.

50 Referring to the drawing, the numeral 8 indicates a wardrobe trunk which is divided medially vertically to form a wardrobe section 9 and another section 10. Rails 11 mounted in the upper portion of the wardrobe section are adapted to hold garment

hangers 12 upon which wearing apparel is draped and suspended. Perforated guide members 13 mounted on the opposite inner sides of the wardrobe section and extending from the front to the rear portion of the 50 section have a retainer bar 14 adjustably connected thereto. One of the outer ends of the bar is provided with a curved projecting pin 15 adapted to adjustably extend through one of the perforations 16 on one 55 side of the section, while the other end of the bar is provided with a manually releasable spring bolt 17 adapted to adjustably extend into the perforations 16 in the bar on the opposite side of the trunk section. 70 The retainer bar is provided with a pad 17 on its inner face which is enclosed by a soft fabric cover 18 extending entirely around the bar to securely hold the pad and to give a finished and ornate appearance to the bar. 75 The rear inner portion of the wardrobe section is also provided with a soft fabric pad 19 held in position by a cover 20, which is firmly secured to the rear portion of the trunk in any manner desired. The fabric 80 preferably used is silk plush or the like, as it will in a manner stick to the garments and not rub or abrade and thereby not injure the garments engaged. The said rear pad is in horizontal alinement with the bar pad 85 so that when garments are suspended between said pads, they will be firmly held thereby.

From the foregoing description, it will be seen that the trunk cushion and retainer is 90 of very simple construction and is well adapted for holding the lower portions of garments which are suspended from garment hangers mounted within a trunk.

What I claim as my invention is:

1. The combination with a wardrobe trunk section having garment hangers for suspending wearing apparel therefrom, of a cushion means for the suspended apparel comprising a soft fabric cushion means positioned in the rear portion of the trunk section beneath the garment hangers, a retainer bar adjustably connected to the trunk section and movable toward and away from the rear cushion and having a front soft 100 fabric cushion means extending in horizontal alinement with the rear cushion means, both of said cushion means adapted to engage the wearing apparel suspended from the garment hangers. 110

2. The combination with a wardrobe trunk section having garment hangers for suspending wearing apparel therefrom, of a cushion means for the suspended apparel comprising an elongated cushion member positioned at the rear of the compartment beneath the garment hangers, a soft fabric cover extending over the cushion and connected to the rear portion of the trunk, 5 guide bars mounted on the opposite sides of the trunk section, a retainer bar adjustably connected to the guide bars and movable toward and away from the rear cushion, an elongated front cushion positioned on the inner face of the retainer bar and extending 10 in horizontal alignment with the rear cushion, and a soft fabric cover extending over the front cushion and the retainer bar, both 15 of said cushions and covers adapted to engage the wearing apparel suspended from the garment hangers.
3. The combination with a wardrobe trunk section having garment hangers for suspending wearing apparel therefrom, of a cushion means for the suspended apparel comprising a soft fabric cushion means fixedly positioned in the rear portion of the trunk section beneath the garment hangers, and a retainer bar adjustably connected to the trunk section in horizontal alignment 20 with the rear cushion means and movable toward and away from said rear cushion means.

In testimony whereof, I affix my signature.

WILLIAM C. CHESNUT.
